[57] CLAIM

The ornamental design for a plate or similar article, substantially as shown and described.

DESCRIPTION

FIG. 1 is a top plan view of a plate or similar article, showing my new design. The plate is formed of a transparent material. The textured bottom decoration would normally be seen through the top in FIG. 1, but has been omitted for convenience of illustration;

FIG. 2 is a bottom plan view thereof;

FIG. 3 is an elevational view taken from the right hand

side of FIG. 1, on an enlarged scale;

FIG. 4 is an elevational view taken from the left hand

side of FIG. 1, on an enlarged scale;

FIG. 5 is an elevational view taken from the top of FIG.

1, on an enlarged scale; and

FIG. 6 is an elevational view taken from the bottom of

FIG. 1, on an enlarged scale.

FIG. 3
